(57) **CLAIM**

The ornamental design for an electronic aerosol, as shown and described.

DESCRIPTION

This application is related by subject matter to copending applications 29/381,222 and 29/381,226, each entitled "Electronic Aerosol," both filed on Dec. 16, 2010, both currently pending.

FIG. 1 is a top perspective view of an electronic aerosol according to our design;

FIG. 2 is a right side view thereof;

FIG. 3 is a left side view thereof;

FIG. 4 is a top plan view thereof;

FIG. 5 is bottom plan view thereof;

FIG. 6 is a front elevation view thereof; and,

FIG. 7 is a rear elevation view thereof.

Any broken line portion of the drawings is included to show environmental subject matter only and forms no part of the claimed design.
